COMBINED ACCUMULATOR BATTERY AND CONNECTOR COVER THEREFOR

Per Enar Lennart Frode, Oskarshamn, Sweden, assignor
to Nife Jungner AB, Oskarshamn, Sweden

Filed Sept. 9, 1975, Ser. No. 611,766

Claims priority, application Sweden Mar. 20, 1975

Term of patent 14 years

Int. Cl. D13—02

U.S. Cl. D26—4

FIG. 1

FIG. 3

FIG. 2

FIG. 4

FIG. 5

FIG. 1 is a perspective view of a combined accumulator battery and connector cover therefor showing my new design,

FIG. 2 is a front elevation thereof,

FIG. 3 is a side elevation thereof,

FIG. 4 is a top view thereof, and

FIG. 5 is a bottom view thereof.

The unillustrated back and side views are identical to the illustrated front and side views of FIGS. 2 and 3, respectively.

I claim:

The ornamental design for a combined accumulator battery and connector cover therefor, as shown and described.
